AUTOMOBILE INTERIOR TRIM PANEL

Herbert J. Woodall, Detroit, Mich., assignor to
 Woodall Industries Incorporated, Detroit,
 Mich., a corporation of Michigan

Application April 17, 1933, Serial No. 666,436

7 Claims. (Cl. 45—138)

My invention relates to improvements in interior trim panels for automobile bodies and particularly to improvements in panel construction whereby an improved panel is provided which is adapted to readily receive from the rear face thereof fastening devices used to secure the panel to its supporting framework and which is also adapted to securely hold such fastening devices while permitting desired adjustability of the fastening devices to meet the necessary requirements of their attachment to the supporting framework of the body.

Panels of this character generally comprise a foundation of composition fiber board or the like over the front face of which fabric or other suitable covering material is attached to give a finished appearance. Suitable fastening devices are provided to secure the finished panel to a supporting framework. A common practice is to provide such a panel adapted to receive fasteners from the rear after the fabric covering has been applied to the foundation board, which fasteners are not visible from the front face of the panel, and which are capable of ready attachment to the frame to securely position the panel thereupon. One well known method is to provide the foundation board of the panel with keyhole apertures, spaced apart along the margin of the panel board, through which apertures headed fasteners are received from the rear and moved into engagement with the panel. Such a construction is shown in Patent No. Re. 18,720.

This practice includes the formation of apertures extending entirely through the foundation board which weakens the board, leaves open spaces underneath the covering material, and, upon insertion of the fasteners, produces protrusions of the covering material outwardly opposite the fasteners.

I propose to provide a panel of this general type with a fastener holding strip extending along the margin, upon the rear face of the panel, which strip is constructed and so secured in place as to permit ready insertion of the fasteners into engagement with the panel, and to securely hold the fasteners to the panel while permitting free adjustability thereof with respect thereto.

Other objects, advantages, and important features will more fully appear from the following specification, appended claims and accompanying drawing, wherein:

Figures 1 is an elevation of a door frame showing my improved panel secured thereto and partly broken away,

Figure 2 is a horizontal sectional view taken on the line 2—2 of Figure 1,

Figure 3 is a sectional view taken on line 3—3 of Figure 2, and

Figure 4 is a fragmentary enlargement in elevation with the material partly broken away.

The panel structure is shown in Figure 1 as 10. It is secured to the framework 12 of the door. As shown in the views this is accomplished by means of fasteners 14. These fasteners may be 10 of any type suitable for the purpose. I have here shown a spring fastener having a head portion 16 and resilient prong portions extending angularly therefrom and adapted to be received through an opening in the flange 18 of the framework of the 15 body adapted to exert tension tending to hold the entire panel structure toward the framework of the body.

My invention does not concern itself with the 20 type of fastener employed and the one here shown is a fastener known to the trade.

I provide a panel which comprises a foundation panel board 20 covered on one side with upholstery cloth 22 which is turned over the edge 25 of the foundation board as at 24 onto the back of the board and adhesively secured thereto so as to hold the covering material in place. In order to provide means to receive and securely hold the fasteners to the panel and to permit of their ready application thereto and of their adhesion with respect to the panel following their 30 application thereto, I provide a strip 26 which is arranged to extend along a margin of the panel upon its rear face as shown in Figures 2 and 4 and which is provided with panel receiving apertures 28 arranged in spaced apart intervals laterally of the strip and in relatively close proximity to its outer margin. These apertures are adapted to receive the head of a fastener therethrough from the rear face. In the construction shown this may be accomplished by rotary motion which causes the head to enter there to be rotated into position through the opening and between the foundation board and the strip as 35 shown in Figures 2, 3, and 4.

The strip is secured to the foundation board by lines of stitching 30 which extend along its interior margin. The outer margin of the strip which is flush with the outer margin of the foundation board is held down by the covering material 16 which is folded from the face of the panel over onto the back of the strip and adhesively secured thereto. There is a certain amount of give in the covering material which permits the strip to be sprung away from the panel board 40 45 50 55

due to stretching of this covering, as shown in Figure 2, and which permits the insertion of the fastener underneath the strip as shown in such figure and in Figure 3.

- 5 In order to insure that the panel will be held snugly against the framework of the body it is necessary that the fasteners be arranged closely adjacent to the outer margin of the panel so as to hold them at such point tightly against the frame. To permit the insertion of the heads of the fasteners underneath the strip it is likewise necessary that there be provided a space within which this may be inserted. This may be accomplished by undercutting a portion on the strip or by providing sufficient space between the strip and the panel board, but it has been found that by adopting the present construction as stitching the strip along its interior margin at a point remote from the fastener apertures and holding the outer margin of the strip in place by the tension of the upholstery cloth that a peculiarly tight grip is exerted upon the strip holding it toward the panel board which holds the fastener in position against accidental displacement while at the same time permitting relative adjustability to accommodate for alignment with the provided apertures in the framework of the body.

What I claim is:

- 30 1. A trim panel comprising a relatively stiff panel board, a fastener holding strip extending along a margin thereof upon the rear face of the panelboard, covering material extending over the front face of the panel and folded over the edge of the panelboard onto said strip and secured thereto and holding the outer margin of the strip yieldingly toward the panelboard, and means connecting the strip along its inner margin securely to the panelboard, said strip being provided with fastener receiving apertures therethrough.
- 35 2. A panel as defined in claim 1 characterized in that the apertures through the strip are arranged closely adjacent to the outer margin of the strip.
- 40 3. A trim panel comprising a relatively stiff panel board, a fastener holding strip extending along a margin on the rear face of the panel and separate at its outer edge from said board, covering material extending over the front face of the panel and folded over onto the back thereof and secured to said strip holding the strip along its outer margin yieldingly toward the panelboard,

means extending through the strip and panelboard securing the strip along its inner margin to the panelboard, said panel having fasteners provided with headed portions received underneath said strip.

4. A trim panel comprising a relatively stiff panel board, a fastener holding strip extending along a margin on the rear face of the panelboard, means connecting the strip along its inner longitudinal edge snugly to the panelboard, means connecting the strip along the outer longitudinal edge yieldingly to the panelboard.

5 5. A trim panel comprising a relatively stiff panel board, a fastener holding strip extending along a margin on the rear face of the panelboard, means connecting the strip along its inner longitudinal edge securely to the panelboard, means connecting the strip along the outer longitudinal edge resiliently to the panelboard, said strip provided with spaced apart fastener receiving apertures spaced in proximity to its resiliently connected edge.

10 6. A trim panel comprising a relatively stiff panel board, a fastener holding strip extending along a margin on the rear face of the panelboard, means connecting the strip securely to the panelboard including means connecting while permitting said strip to be sprung slightly away from the panelboard at spaced apart points adjacent to the outer margin of the strip, and fasteners having headed portions engaged by the said strip and panel at such points whereby the head of the fasteners is held toward the panelboard by the strip against accidental displacement while having relative adjustability with respect thereto.

15 7. A trim panel comprising a relatively stiff panel board, a fastener holding strip extending along a margin upon the rear face of the panelboard, covering material extending over the front face of the panel and folded over the edge thereof onto said strip and secured thereto and holding the outer margin of the strip yieldingly toward the panel board, means connecting the strip along its opposite margin securely to the panelboard, headed fasteners carried by said strip having 20 their headed portions arranged thereunderneath adjacent to the outer margin thereof and held by the strip toward the panelboard against accidental displacement while having relative frictionally resisted adjustability underneath the 25 strip with respect to the panel.

HERBERT J. WOODALL.
